UNITED STATES PATENT OFFICE.

EPHRAIM MILLER, OF CHICAGO, ILLINOIS, ASSIGNEE, BY MESNE ASSIGNMENTS, TO
JOHN BERNET, OF CHICAGO, ILLINOIS.

LOCK FOR CONTROLLING-LEVERS.

1,265,355.

Specification of Letters Patent. Patented May 7, 1918.

Application filed April 17, 1916. Serial No. 91,563.

To all whom it may concern:

Be it known that I, EPHRAIM MILLER, a subject of the King of Great Britain, and resident of Chicago, in the county of Cook 5 and State of Illinois, have invented certain new and useful Improvements in Locks for Controlling-Levers, of which the following is a specification.

This invention relates to improvements in 10 a device to be used for locking the controlling levers of automobiles, or if desired, for locking such levers of other kinds of machines or machinery, and it consists in certain peculiarities of the construction, novel 15 arrangement and operation of the various parts thereof as will be hereinafter more fully set forth and specifically claimed.

The main object of the invention is to provide locking means for controlling levers, 20 whereby such a lever may be readily and securely locked in a certain fixed position, so that, the machine which it controls can not be set in motion or caused to operate by unauthorized persons, yet so that the lever may 25 be easily released and the lock maintained in such position with respect to the lever as to enable the latter to be freely operated. Another object is to so construct the parts of 30 the device as to provide a housing for the interior elements thereof, to the end, that dust will be excluded therefrom. Other objects and advantages of the invention will be disclosed in the subjoined description and explanation.

35 In the accompanying drawings, which serve to illustrate the invention—

Figure 1 is a plan view of the lock showing it mounted on the controlling lever and illustrating the latter in section.

40 Fig. 2 is a view in side elevation of a portion of the lever, a part of the support or bearing therefor, illustrating the lock in its lowered or locked position.

Fig. 3 is a vertical sectional view taken on 45 line 3—3 of Fig. 2 looking in the direction indicated by the arrows and showing the parts in their locked positions.

Fig. 4 is a similar view taken on the same line and looking in the same direction, but 50 illustrating the parts in their unlocked positions.

Fig. 5 is a plan sectional view taken on line 5—5 of Fig. 3.

Fig. 6 is an enlarged detached perspective

view of the slidable or locking sleeve of the 55 device, and

Fig. 7 is a detached perspective view of the locking bolt which fastens and releases said sleeve.

Like numerals of reference refer to like 60 parts throughout the different views of the drawings.

The reference numeral 10 designates a controlling lever, for instance, for an automobile, which lever is suitably connected at 65 its lower end or portion to a connection which leads to the transmission gearing of the automobile or machine, which connection and gearing is not herein shown. Surrounding the lower portion of the lever 10 is 70 a support or bearing 11 therefor, which may be mounted in an upright manner on the floor of the chassis of the automobile at a suitable point so that the lever 10 may be conveniently reached by the operator for 75 his manipulation in starting, changing the speed and stopping the machine, when the device is used in connection with an automobile, or said support may be suitably mounted on a desired part and at a convenient place on any other machine to which the device may be applicable. As shown in Figs. 3 and 4 of the drawings the bearing or support 11 is provided with an upwardly tapered cavity 12 within which is 80 snugly fitted a rounded or substantially spherical enlargement 13 with which the lever 10 is provided. The upper end of the support or bearing 11 is provided with a downwardly tapered opening 14 which communicates with the cavity 12 and as shown is considerably larger than the lever 10 around which the opening 14 is located, so as to permit of considerable movement of the lever in any direction. At a suitable 90 distance above the enlargement 13, the lever 10 is by preference provided with screw threads 15 to engage an internally screw threaded collar 16 which depends from the upper portion of the housing 17 which has 100 its lower portion outwardly and downwardly flared as at 18 so as to closely embrace the rounded or upwardly and inwardly inclined portion 19 of the upper part of the support or bearing 11, as will 105 be clearly understood by reference to Figs. 2 to 4 inclusive of the drawings. The housing 17 is provided at a suitable point near

its upper end with a diagonally disposed slot 20 through which is extended a pin or rod 21, the inner end of which is in screw engagement with the upper portion 5 of a slidable or locking member 22, the upper end of which closely but loosely surrounds the collar 16, while the lower end of said sleeve surrounds, in a like manner, that portion of the lever 10 just below the screw 10 threads thereon. The lower end of the sleeve 22 is downwardly and inwardly tapered as at 23, so as to fit snugly in the opening 14, when said sleeve is in its lowered position, as shown in Fig. 3 of the 15 drawings. The sleeve 22 is provided in its wall with an opening 24 and located at a suitable point, when said sleeve is raised as shown in Fig. 4, to permit of access through the slot 20 to a screw 25 which is passed 20 through a suitable opening in the collar 16 of the housing 17 and engages a suitable opening in the lever 10, as is clearly shown in Figs. 3 and 4 of the drawings. In its wall, and at a point about diametrically opposite the rod or handle 21, the sleeve 22 is provided with a socket 26 to receive the inner end of the locking bolt 27, the purpose and operation of which will be presently described. As shown in Fig. 6, the sleeve 25 25 30 35 40 45 50 55 60 65 70 75 80 85 90 95 100 105 110 115 120 125 130

22 is provided with an external recess 28 in the lower portion of which is located a projection 29 to which one end of a spring 30 is secured, the other end of which spring is secured to an inwardly extended projection or screw 31 which is located in the upper portion of the housing 17 at such a point therein as to extend into the recess 28 of said sleeve as will be readily understood by reference of Fig. 5 of the drawings, and so as to hold the sleeve 22 under tension for rotary movement on the collar 16 while said sleeve is engaged by the locking bolt 27 of the lock of the device. As shown in the drawings, the upper portion 45 of the housing 17 is provided with an enlargement 32 which is provided with a vertical opening 33 in which is fitted a barrel 34 of a lock of the ordinary or any preferred construction, which barrel has in its outer end a plate 35 provided with a key hole 36 for the reception of a key to be used for engaging and moving, through the medium of suitable tumblers contained in the barrel 34, a projection 37 which extends downwardly from the barrel 34 and is adapted to engage the inner surface of a cross bar 38 horizontally and transversely mounted on the upper portion of the bolt 27 of the lock. The bolt 27 is provided near its inner end with a transversely extended rod 39, and said bolt is horizontally mounted for reciprocal movement in the lower portion of the enlargement 32, and has its inner end projected toward the wall of the sleeve 22 at a point to engage the opening

26 in said sleeve, when the latter is turned so as to bring said opening in alinement with the bolt 27, as is obvious by reference to Figs. 3 and 5 of the drawings. The bolt 27 is located in a socket 40 of a keeper 41, 70 which keeper is provided on each side of said socket with a recess 42 in each of which is located a spring 43 which rest at one of their ends against the transverse rod 39 and at their other ends against the 75 outer ends of said recesses. Thus it will be seen that the tension of the springs 43 will normally press the locking bolt 27 inwardly, but that when the projection 37 of the lock is moved by means of a key which controls said lock, so as to cause said projection to move outwardly, the locking bolt 27 will be retracted and disengaged from the socket 26 therefor in the locking or slidable sleeve 22, which sleeve will then be 80 slightly rotated by the action of the spring 30 on the collar 16, thus removing the socket or opening 26 out of register with the inner end of the bolt 27 and permitting the latter to rest against the wall of said sleeve. 90

From the foregoing and by reference to the drawings it will be understood and clearly seen, that, assuming the parts to be positioned as shown in Fig. 4, or in their unlocked positions it will be understood that 95 the lever 10 can be moved in almost any direction so as to control the transmission gearing to which said lever is connected, but when it is desired to lock the lever 10 in a neutral or inoperative position, the locking sleeve 22 can be caused to engage, at its lower end, the opening 14 in the upper end of the support or bearing 19, by simply pressing downwardly on the projection 21, which operation will cause the sleeve 22 to 100 rotate on the collar 16 and lever 10, thus bringing the opening 26 into register with the locking bolt 27, which by reason of the springs 43 which actuate said bolt will be forced into said opening and thus securely 105 lock the sleeve 22 in its lowered position, when it is obvious that the lever will be held against movement. To release the lever, a key may be inserted in the opening 36 of the lock, when by turning said key in the 110 proper direction the projection 37 will be moved outwardly thus retracting the locking bolt 27 from engagement with the sleeve 22, when by reason of the tension of the spring 30, said sleeve will be rotated and 115 raised to its normal position and thus held by said spring until it is again pressed downwardly.

Having thus fully described my invention, what I claim as new and desire to secure by Letters Patent is—

1. In a lock for controlling levers, the combination with a lever of a bearing-support therefor, a lock-carrying member mounted on the lever to move therewith, a 130

spring actuated bolt mounted on said member and adapted to be moved toward and from said lever, a sleeve rotatably and slidably mounted on the lever above said support and having means to engage the same, means to retract said bolt, and resilient means connected to said member and to said sleeve adapted to automatically rotate and raise said sleeve into released position when said bolt is retracted.

2. In a lock for controlling levers, the combination with a lever, of a bearing-support for the lever having a flared opening in its upper end, a lock-carrying member surrounding said lever and the upper portion of the bearing-support and fixed to the lever, a slidably and rotatably mounted sleeve surrounding the lever and located within said member, a spring connected to 20 said member and sleeve to rotate and raise said sleeve out of engagement with the opening of the support, means for rotating and lowering said sleeve into locking position, a locking bolt carried by said member and 25 adapted to be automatically moved into locking engagement with said sleeve when the same is lowered, and means to retract said bolt whereby said spring acts automatically to return said sleeve to release position.

3. In a lock for controlling levers, the combination with a lever, of a bearing-support for the lever having a flared opening in its upper end and rounded upper exterior, a lock carrying member surrounding said lever above the support and fixed to the lever, said lock carrying member having a diagonally disposed slot in its wall, a slid-

ably and rotatably mounted sleeve surrounding the lever and located within said member, a rod or pin secured to said sleeve and extended through said slot, a spring connected at one of its ends to the sleeve and at its other end to said member and within the same, a locking bolt carried by said member 45 and adapted to be moved toward and from the lever and into and out of engagement with said sleeve, and means to move said bolt.

4. In a lock for controlling levers, the combination with a lever having a rounded enlargement thereon, of a bearing-support for the lever housing said enlargement and having a flared opening in its upper end and rounded upper exterior, a lock carrying member surrounding said lever above the support and fixed to the lever, said member having a portion embracing the rounded part of said support, said member having a diagonally disposed slot in its wall, a slidably and rotatably mounted sleeve surrounding the lever and located within said member and having its lower end downwardly tapered to fit in the opening of said support, a rod or pin secured to said sleeve and extended through said slot, a spring connected at one of its ends to the sleeve and at its other end to said member and within the same, a spring actuated locking bolt carried by said member and adapted to be moved 60 into and out of engagement with said sleeve, and means to retract said bolt.

EPHRAIM MILLER.
